CLAIM

The ornamental design for a base for a shade pole, as shown and described.

DESCRIPTION

FIG. 1 is a perspective view of a new design for a base for a shade pole.

FIG. 2 is a right side view of FIG. 1.

FIG. 3 is a left side of FIG. 1.

FIG. 4 is a front view of FIG. 1.

FIG. 5 is a rear view of FIG. 1.

FIG. 6 is a top view FIG. 1.

FIG. 7 is a bottom view of FIG. 1.

FIG. 8 is a perspective view of another embodiment of the new design for a base for a shade pole.

FIG. 9 is a right side view of FIG. 8.

FIG. 10 is a left side view of FIG. 8.

FIG. 11 is a front view of FIG. 8.

FIG. 12 is a rear view of FIG. 8.

FIG. 13 is a top view of FIG. 8; and,

FIG. 14 is a bottom view of FIG. 8.

The dotted broken lines depict portions of the article that form no part of the claimed design. The dashed broken lines depict stitching on the article that is being claimed. The dash-dot-dash broken lines depict the bounds of the claim.

1 Claim, 8 Drawing Sheets
